(76) Inventor: **Vincent Peng**, 322 S. Ynez Ave., #C, Monterey Park, CA (US) 91754

(57) **CLAIM**

The ornamental design for a vehicle steering wheel cover having a design of illuminated flames made of light-transmissive material, as shown and described.

(**) Term: **14 Years**

DESCRIPTION

(21) Appl. No.: **29/190,353**

FIG. 1 is a front perspective view of a vehicle steering wheel cover having a design of illuminated flames made of light transmissive material showing my new design.

(22) Filed: **Sep. 20, 2003**

FIG. 2 is a front elevational view thereof; and,

(51) LOC (7) Cl. **12-16**
(52) U.S. Cl. **D12/177**
(58) Field of Search D12/177, 176,
D12/175; 74/552, 558, 558.5

FIG. 3 is an enlarged right side elevational view thereof. The broken line showing of environmental structure is for illustrative purposes only and forms no part of the claimed design.
